UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

TYPOGRAPHICAL MACHINE.

1,144,822.

Specification of Letters Patent. Patented June 29, 1915.

Application filed February 6, 1915. Serial No. 6,539.

To all whom it may concern:

Be it known that I, PHILIP T. DODGE, a citizen of the United States, residing at New York, in the county of New York and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436532, to O. Mergenthaler, wherein circulating matrices are released from a magazine in the order in which their characters are to appear in print and then assembled in line, the composed line transferred to the face of a mold, the mold filled with molten metal 20 to form a slug or linotype against the matrices which produce the type characters thereon, and the matrices thereafter elevated and returned through a distributing mechanism to the magazine from which 25 they started.

More particularly, it relates to that class of machines employing a plurality of magazines containing matrices of different font or face.

30 One of the principal objects of my invention is to provide an arrangement whereby different selected pairs or pluralities of magazines may be used conjointly, the idea being to permit the mixture of different fonts or faces in the machine for the production of matter of various descriptions, after which the matrices are returned to 35 their appropriate magazines.

It has already been proposed to employ 40 two fixed distributors and a plurality of magazines which can be moved to bring different pairs thereof into operative relation to the distributors. According to my present invention, however, I propose to 45 provide a series of fixed magazines and two or more distributors which may be moved relatively to the magazines so as to be brought into operative relation to different selected pairs or pluralities thereof. Specifically, I mount the two distributors upon separate supporting frames so 50 that each may be connected to different magazines independently of the other, with the result that the two distributors may be 55 made to cooperate with any two magazines

of the series (a capability not present in prior constructions), thus greatly increasing the flexibility of the machine and providing a greater assortment of faces which may be mixed therein.

In the accompanying drawings, I have shown my invention in preferred form and by way of example and as applied to a machine of the class stated, but obviously many changes and variations may be made therein, and in its mode of application, which will still be comprised within its spirit. Thus, it may be applied to other forms of typographical machines, such as typesetters, type-casters and the like, which handle type or dies instead of matrices. Generally speaking, I desire it to be understood that I do not limit myself to any specific form or embodiment, except in so far as such limitations are specified in the claims.

Referring to the drawings: Figure 1 is a rear view, partly broken away, of a portion of a linotype machine, having my invention applied thereto; Fig. 2 is a section taken on the line 2-2 of Fig. 1; Fig. 3 is a side view of the machine, partly broken away; Fig. 4 is a similar view broken away in a different manner; and Fig. 5 is a section on the line 5-5 of Fig. 1.

I have limited the drawings to such parts of the machine as are concerned directly with my invention. The assembling and casting devices, etc., may be of any well-known or approved construction.

The matrices X are stored according to font in the magazines A¹, A², A³ and A⁴, which are mounted in the stationary frame A suitably supported in the machine frame. After the matrices have been composed in line and presented to the casting mechanism, they are carried upward and delivered to the font-separator E, which assorts them according to font and drops them into one or the other of the tubes E¹ and E² leading to the distributors C and D, respectively.

The parts so far described, except as hereinafter pointed out, are or may be of any suitable or well-known construction. It will be understood, of course, that each of the distributors comprises, as usual, a longitudinally extending bar having tooth combinations to release the matrices at different points in its length according to character, and a set of rotary screws, which are geared

together and serve to propel the matrices along the bar until they reach the proper point.

As previously stated, it is the purpose of my invention to arrange the two distributors so that they may be operatively connected to different selected pairs of magazines. To this end, the distributor C in its entirety, is mounted upon a pair of brackets C² arranged to slide upward and downward in the machine frame, the brackets being formed with tongues C³ which engage in grooves or guideways F in the opposite sides of the framework. Similarly, the entire distributor D is mounted upon a pair of brackets D² having tongues D³ slidably engaged in the same grooves F. As a result of this arrangement, the two distributors may be shifted up and down so as to be brought into operative relation to any selected pair of magazines at will. For instance, in Fig. 4 the two distributors are shown as connected to the uppermost and lowermost magazines A¹ and A⁴, while in Figs. 2 and 3, they are shown as connected to the two upper magazines, A¹ and A². Similarly the distributors may be connected to other selected pairs of magazines, their independent mounting permitting them to coöperate with any two magazines of the series, there being six different pairs thus available in a series of four magazines. Obviously, by increasing the number of magazines, the number of pairs capable of selection will be multiplied.

It is to be noted that the delivery tubes E¹ and E² leading from the font separator E are telescopic or flexible in order to permit the free and unimpeded movement of the distributors in the manner just described.

Any suitable mechanism may be employed for shifting the distributors and for holding them in their shifted position. In the present instance, I provide in connection with the distributor C a pair of levers G, connected by pin-and-slot connections G¹ to the brackets C², and fast upon a rock shaft G² mounted to turn in bearings in the upstanding portions H of the magazine-frame A. One of the levers G is formed with an arm G³ pivoted to a link G⁴ of a toggle system, which has its other link G⁵ pivoted to the frame A, the two links G⁴ and G⁵ being joined by a short stud G⁶. A rod G⁷ connects the toggle system with a hand lever G⁸ arranged at the front of the machine and having a detent G⁹ adapted to engage in one or another of the notches of the sector G¹⁰. By shifting the hand lever in one direction or the other, the distributor C will be moved up or down and brought into operative relation to one or another of the three uppermost magazines, A¹, A², A³, the detent G⁹ serving to hold the parts in their shifted position. A similar arrangement for the distributor D is employed, consisting of a pair

of arms J connected by pin-and-slot connections J¹ to the brackets D², and fast upon a rock shaft J² mounted to turn in bearings in the upstanding portions H. One of the levers J is provided with an arm J³ connected to a toggle system J⁴, which in turn is connected by the rod J⁵ to a hand lever J⁶, having a detent J⁷ adapted to engage in one or another of the notches of the sector J⁸ arranged at one side of the sector G¹⁰.
The operation of the parts will be clear from the foregoing. By shifting the hand levers G⁸ and J⁶ in the proper manner, the distributors may be brought into operative relation to any pair of magazines desired.
It is pointed out that channel entrances C⁴ and D⁴ are employed to conduct the matrices from the distributors to the selected magazines, the entrance C⁴ being carried by the supporting brackets C² of the distributor C, and the entrance D⁴ by the supporting brackets D² of the distributor D. The two entrances are pivotally connected to their respective supporting brackets, as at C⁵ and D⁵, so as to be swung downward to give access to the distributors. Owing to the movable nature of the distributors, the actuating mechanism therefor must be of such character as to maintain its connection therewith in any of their different positions. In the present instance, one of the screws of the distributor C is provided with a sprocket wheel O, and one of the screws of the distributor D with a sprocket wheel P, the two sprocket wheels being driven by a continuous sprocket chain M¹ engaging a pair of sprocket wheels M³. The lower sprocket wheel is loosely mounted upon a stud M⁴ projecting from the framework, while the upper one is fast upon one end of a shaft M⁴ journaled in the framework, and carrying at its other end a further sprocket wheel M⁵ driven by a sprocket chain M², which is operated from the shaft M¹ carrying the driving pulley M. It will be noted that the sprocket chain M¹ extends throughout the range of movement of the two distributors, so that they are free to be shifted to any of their different positions without disturbing the driving connections. The shaft M¹ is also geared to a shaft N which operates the screws of the font separator E through the intermediate gearing N¹, shown in detail in Fig. 5.

While in the accompanying drawings I have shown my invention in connection with a series of inclined magazines, it will be understood that it may be applied to a machine employing vertically disposed magazines, in which event the distributors would be moved horizontally instead of vertically as herein. It will also be understood that any desired form of font separating mechanism may be employed for delivering the matrices to one or the other of the distribu-

ters, the only requirement in this respect being that the matrices of the selected magazines be separated in an appropriate manner for distribution into the proper magazines.

5 These and various other changes will readily suggest themselves to those skilled in the art without departure from the scope of my invention.

It will further be understood that the general organization of my present machine may be made use of in various ways. For instance, for different languages and for different classes of work it is sometimes desirable to have the matrix characters differently arranged in the magazines and the keyboard, which arrangement involves an alteration in the distributors or in the matrices. It will be apparent that my present machine would be specially adapted for such use, in that, if desired, matrices of one grouping may be delivered into one magazine and matrices of a different grouping into another magazine. It may also be noted that the construction is such that either one of two distributors may be brought into operative relation to a given magazine, which feature would allow, for example, matrices of one grouping or another to be delivered to the same magazine. As previously stated, my invention is not limited to any use or adaptation of the general construction except in so far as such limitations are specified in the claims.

Having thus described my invention, its construction and mode of operation, what I claim and desire to secure by Letters Patent of the United States, is as follows:

1. In a typographical machine, the combination of a plurality of magazines, and two distributors movably arranged so as to be brought into operative relation to different selected pairs of said magazines.

2. In a typographical machine, the combination of a plurality of magazines, two distributors, and means whereby the two distributors may be connected to any selected pair of magazines of the said plurality.

3. In a typographical machine, the combination of a plurality of magazines, and two distributors, the said distributors being movable independently so as to be brought into operative relation to any selected pair of magazines of said plurality.

4. In a typographical machine, the combination of a plurality of magazines, two distributors movably arranged so as to be brought into operative relation to different

selected pairs of magazines, and a font separator for delivering the matrices to one or another of the distributors, as required.

5. In a typographical machine, the combination of a plurality of magazines, two distributors movably arranged so as to be brought into operative relation to different selected pairs of said magazines, a font separator mounted in a fixed position in the machine, and flexible tubes leading from the font separator to the respective distributors.

6. In a typographical machine, the combination of a plurality of magazines, distributing mechanism, and means whereby the distributing mechanism may be operatively connected to any selected pair of magazines of the said plurality.

7. In a typographical machine, the combination of a plurality of magazines, and distributing mechanism coöperating with one pair of said magazines, the said distributing mechanism being movably arranged so as to be connected to a different pair of magazines at will.

8. In a typographical machine, the combination of a plurality of magazines, two distributors, intermediate channel entrances for conducting the matrices from the distributors to the corresponding magazines, and two separate and independently movable supporting frames, one for each distributor and its respective channel entrance.

9. In a typographical machine, the combination of two distributors, each movable independently to different operative positions, and means for actuating the distributors in any of their different positions.

10. In a typographical machine, the combination of two distributors and actuating mechanism connected thereto, the distributors being movable independently to different operative positions without disturbing their connection with the actuating mechanism.

11. In a typographical machine, the combination of a magazine, and two distributors movably arranged so that one or the other may be brought into operative relation to the magazine.

In testimony whereof, I have affixed my signature in presence of two witnesses.

PHILIP T. DODGE.
